METHOD AND MECHANISM FOR CONTINUOUSLY FORMING LIQUID-IMPERVIOUS PLUGS IN EXTRACTION UNITS

Michele Bonotto, Evansville, Ind., assignor to Extractol Process, Ltd., Wilmington, Del., a corporation of Delaware

Application July 19, 1938, Serial No. 219,973

7 Claims. (Cl. 23—268)

This invention relates to improvements in methods and mechanisms for continuously forming liquid-impervious plugs in extraction units and constitutes an improvement in the method and apparatus of my prior application Serial No. 94,582, filed August 6, 1936.

In my said earlier application, I have shown a plug-forming mechanism and described a plug-forming method by which solvent-soaked solid material from an extraction unit is continuously fed by a conveyor screw of relatively small capacity, (thus feeding a relatively small feed of such solid material), into a packing conduit having a packing screw of larger capacity than the volume of said feed of solid material, and a plug is incrementally formed near the valved end of said packing conduit by continuously pressing, with said packing screw, the relatively small feed on one end of said plug in said packing section while continuously forcing the opposite end of said plug through said valved end of said relatively large capacity conduit to discharge material from the extraction unit, all of the work being done along a single axis.

In operating a device such as described in the application above-mentioned, I have found that a definite relationship exists between the capacity of the screw that feeds from the extraction tank into the packing conduit (which I shall hereinafter call the feeder-screw), and the capacity of the packing screw, and if for some reason the capacity of the packing screw is decreased, a choking action occurs in a zone in the packing conduit adjacent to the feed-opening between said packing conduit and the extraction tank. With some materials such a decrease in capacity in the packing screw does not take place, but with other material and especially with materials of sticky character, such as distillers' grain, difficulty of that sort is apt to occur.

To avoid such difficulties in installations such as shown in said application, the diameter of the packing screw should be calculated to have a capacity of, say, four or five times that of the feeder-screw. However, in an extraction unit of, for example, say one hundred (100) tons per day output, the dimension of the packer-screw, in order to assure that the quantity of material passing through the said feed opening between the extraction tank and the packing conduit will be less than the quantity of material that the packer-screw is able to pack and expel, would be too big for practical operation, and the problem is presented of procuring the necessary increase in the capacity of the packer-screw over the

feeder-screw without unduly increasing the size of the packer-screw. I have found that this problem can be solved by increasing the speed of the packer in relation to the speed of the feeder-screw, or by increasing both the relative speed and the relative diameter of the packer-screw over the feeder-screw. While this result may theoretically be accomplished if positioning of the feeder-screw and packer-screw are along the same axis, I have found that it is desirable that the two screws be mounted on independently-driven shafts positioned on different levels and preferably that the independently-driven shaft of the packer-screw be positioned in the same vertical plane as the feeder-screw shaft and in installations where the solid material being extracted is heavier than the solvent, it is desirable that the packer-screw should be located directly beneath the feeder-screw, and in all cases an intermediate feed chamber or feed box should be provided. Obviously, in a construction where the capacity of the packer-screw is increased by increasing the speed thereof, the packer and feeder-screws may be of the same or different diameters.

With these and other objects in view, the invention comprises the combination of members and arrangements of parts so combined as to co-act and cooperate with each other in the performance of the functions and the accomplishment of the results herein contemplated, and comprises in one of its adaptations the species or preferred form illustrated in the accompany drawings, in which:

Fig. 1 is a vertical section partly broken away, of an extraction unit for use with a solvent of specific gravity lower than the extracted material and showing my improving plug-forming mechanism embodied therein;

Fig. 1^a is a similar fragmentary section of the outer end of the packing mechanism shown in Fig. 1;

Fig. 2 is a fragmentary view showing a modified form of the packing mechanism shown in Fig. 1;

Fig. 3 is a horizontal section on the line 3—3 of Fig. 1, partly broken away, of the feeding and packing mechanism shown in Fig. 1;

Fig. 4 is a vertical section on the line 4—4 of Fig. 1, looking in the direction of the arrows;

Fig. 5 is a vertical section, partly broken away, of an extraction unit showing another slightly modified form of feeding and packing mechanism;

of still another modified form of feeding and packing mechanism embodying my invention;

Fig. 7 is a section on the line 7-7 of Fig. 6, looking in the direction of the arrows;

5 Fig. 8 is an enlarged fragmentary vertical section of the end of a packing conduit and adjacent parts employed by me, and Fig. 9 is a section on the line 9-9 of Fig. 8.

Referring now to these drawings which illustrate a preferred embodiment of my invention, one way to avoid the difficulties and accomplish the results hereinabove described is to modify the mechanism described in application Serial No. 94,582, in such manner that the speed of 10 the packer-screw will be higher than the speed of the feeder-screw, so that the packer-screw, by such increased speed, will handle more material than the feeder-screw is able to feed through the said feed opening, and in Figs. 6 15 and 7 I have illustrated an extraction unit, (which will hereinafter be more particularly described), having, in a manner similar to that described in my said application, the feeder and packer-screws arranged along a single axis but 20 being modified to permit the packer-screw to be rotated at a speed increased over that of the feeder-screw. However, an arrangement of that kind will require a bearing inside the packing conduit with the consequent danger of causing 25 a choke. But apart from that difficulty, a modification of this kind will theoretically solve the 30 problem.

From the practical operating point of view, however, it is preferable in order to enable the 35 speed of the packer-screw to be increased and run at a higher rate than the speed of the feeding screw, that instead of the action described in my application Serial No. 94,582, taking place along a single axis of the shaft driving the 40 packer-screw and the feeder-screw, such action shall take place on two levels, with the packer-screw being positioned below the feeder-screw, and with this end in view I preferably provide, in the extraction tank, a feeder-screw of given 45 size or diameter and preferably driven by an independent motor at a rate of speed which represents the working capacity of the extractor, and I feed the exhausted and discharged material from the extraction tank into and through a 50 packer-feed chamber or box preferably located outside the extraction tank and then into the packer-conduit on a packer-screw positioned in said packer-conduit below and in the same vertical plane as the said feeder-screw, the packer- 55 screw being mounted on a shaft also preferably driven by an independent motor at such a speed as to assure, at any given moment, that the material passing through the material discharge or feeding opening and into the feed box may be 60 readily evacuated from said box and pushed against the cone valve and thereafter discharged into a suitable hopper from which such material will go to the dryers.

In Figs. 1 to 5, I have illustrated several constructions showing mechanisms with the screws at different levels which I will now more particularly specify.

In Fig. 1, I indicates an extraction unit, the extraction section 1^a of which is preferably divided 65 into a series of intermingling zones a, b, etc., preferably separated from each other by discs 3, having vertically non-registering and radially-disposed apertures 3'. The discs are mounted on a central shaft 4 and preferably revolve in a 70 horizontal plane without causing the solid mate-

rial to revolve therewith, and to prevent such movement of material with the discs, I preferably provide within the tank 1, scraper arms 5 which are suitably supported within the tank to provide a positive stop against such revolving movement of material with the revolving discs. This mechanism more particularly forms the subject-matter of a still earlier application Serial No. 48,646, filed November 7, 1935, and is here illustrated merely to show one form of extraction unit 75 in which the solid material to be extracted and the solvent are caused to be moved continuously in counter-current through the extraction section and in connection with which the solid exhausted material is formed into an impervious 80 plug at the discharge end thereof. In the embodiment illustrated, the packer-screw is of larger diameter than the feeder-screw and said screws are mounted at different levels, one below the other, but in the same vertical plane. In the unit 85 shown, after the material passes through the zones a, b, etc., it is caused to pass through a bottom expansion chamber 8 which is preferably, as illustrated more particularly in Figs. 3 and 4, provided with inclined sides 8', 8", merging into 90 a trough or casing 8^b, within which is mounted a horizontally-disposed conveyor screw 10' which is preferably perforated and mounted on a horizontal shaft 11' which is rotated independently 95 of the rotation of the packer-screw hereinafter described, from any suitable source of power. As shown, the shaft 11' is rotated through beveled pinions 11^a, 11^b, the latter of which is connected with a vertical shaft S preferably extending to an independent source, not shown. As illustrated, a 100 packer feed-box F is suitably supported and disposed outside the extraction tank in alignment with the discharge aperture 1^a of said extraction tank and the shaft 11' is supported at its inner end in a bearing 11^c connected to the lower end 105 of the extraction tank, while the outer end of said shaft 11' extends into and passes through a feed chamber f of said feed box F and is supported in a bearing 11^d on the outer surface of said box.

The function of the feeder-screw 10' is to unload the exhausted material from the bottom of the extraction tank into the chamber f of the box F and, as only a relatively small amount of horse power will be necessary to do this work, I 110 preferably apply, to the shaft S, an independent motor which will have a rate of speed, as aforesaid, sufficient to operate the screw at a rate 115 commensurate with the discharge capacity of the extractor.

In said preferred form of my invention shown 120 in Figs. 1 and 1^a I provide, below the feed screw 10' and preferably in the same vertical plane as said screw, a packer-screw 12^a revolving within one end of a packer conduit 12 which is connected with the feed chamber f by a feed opening f'. The packer-screw 12^a is mounted independently of the feed-screw 11' and is supported at 125 one end in a bearing b and the other end in a bearing b', on a hopper H connected with the outer end of the packing conduit 12 and through which said shaft extends, and at all of the bearings I preferably provide conventional stuffing boxes to maintain fluid-tight joints with the shafts. The packer-shaft 12^b is, as shown, 130 driven independently of the shaft 11' through pinions 12^c, 12^d, by shaft S' which is preferably driven by an independent motor.

The horizontally-disposed and perforated conveyor screw 10 is thus rotated in its trough 135 8^b

and conveys or moves all solid material that passes to the bottom of the tank 1 and into the chamber *f* of the box *F* from which, in accordance with my present invention, the material is fed by gravity through the opening *f'* into the packing conduit *12* and on a rear portion of the screw *12a* situated below said opening *f'*. In the form shown in Fig. 1, the packer-screw is thus not only independently supported and driven independently from the screw *10* but is, as aforesaid, larger or greater in diameter than the feed screw *10*.

Exhausted solid material from the extraction column or tank sometimes has a tendency to flow too freely through the opening *1a'* and into the chamber *f* of the box *F* and in order to stop such free flow of material, I have, in the form of my apparatus shown in Figs. 1 to 4, provided a baffle plate *B* preferably of arcuate conformation and, as shown, suitably connected along the top edge of the circular opening *1a'* and extending inwardly therefrom into the extraction tank over the feeder-screw. This same result may be achieved by extending a section of a discharge conduit outwardly beyond the opening *1a'* and in Fig. 5 I have shown such a discharge-section conduit *B'* with the feed screw projecting therethrough and into the chamber *f*. Such a section of conduit will take the place and serve the function of the baffle *B* shown in Figs. 1 to 4.

The material passing through the feed opening *f'* on the rear portion of the screw *12a* is then moved forwardly and packed into an incrementally-packed liquid impervious plug near the outer end of said packer-conduit *12*, and, as shown, in a plug-forming chamber *13* disposed in said packer-conduit between the end of the packer-screw *12a* and a conical valve *14* slidably mounted on the shaft *12b* and arranged to exert pressure against the outward movement of the solid material through the packer-conduit to form a plug and then to provide, at the outer end of the plug, a yielding pressure to permit discharge of the outer end of said plug into the hopper *H*.

Controlled pressure on the valve *14* to force the same toward its seat at the outer end of the packer-conduit is preferably supplied by hydraulic means, such as an oil cylinder *15*, the hollow piston stem *15'* of which abuts the end of said valve *14* as shown in Fig. 1a. The hydraulic cylinder *15* is of conventional construction and is shown more or less schematically with inlet and outlet ports *15a*, *15b*, but it will be understood that the usual pressure-controlling and indicating means, not shown, may be provided.

The bore of the packer cylinder is preferably provided with a series of straight ribs or strips *16* extending parallel to the axis of the shaft *12b* so as to provide a slight space between a cylinder and the screw to permit return or rearward movement in the packing conduit of liquid squeezed from the material, and these ribs also assist the forward movement in the conduit of the solid material when the same has a tendency to pack between the flights of the packer-screw.

It is desirable that the portion of the shaft *12b* which extends through the packing chamber *13*, be tapered outwardly toward the valve *14*. Such taper is desirable because there is a tendency for the liquid in the material, at the packing side of the plug, to form a channel surrounding the shaft and thus to pass through the plug and in order to overcome this difficulty and to avoid

formation of such a channel the said shaft is, as aforesaid, provided with a taper at *12b*.

In the embodiment of my invention shown in Fig. 1, I preferably provide a solvent-return channel *F'* communicating between the feed box *F* and the extraction tank *1a* to permit solvent squeezed out of the material evacuated and being formed into a plug to return to the tank, and said unit is provided with a solvent inlet *I*, a solvent pump *P*, a miscella outlet *O* and a feed-hopper *FH*. The shaft *4* is rotated through pinions *4'*, *4a* and shaft *S²* connected with any suitable power source.

In Fig. 2, I have shown, in fragmentary section, a construction in which pressure on the valve at *15* the end of the packer-conduit *12* is provided by spring *14a* the degree of pressure being variable by the nut *14b* mounted on a rear reduced and threaded portion *12c* of the shaft *12b*, said shaft preferably being supported in the same way shown in Figs. 1 and 1a.

In Fig. 5, I have shown a plug-forming mechanism in which a packer-screw *12a'* has a smaller diameter than the feeder-screw *10a* and the feeder *10* may therefore have very slow speed in comparison with that of the packer-screw *12a'*. A combination such as this is desirable when the material to be withdrawn from the extractor is of very light specific gravity and which, for that reason, has a tendency to be set in motion by the vortex which would be created by a fast revolving feeder-screw. In such a case, the small-diameter fast-revolving feeder-screw would not be able to unload through the discharge opening *1a* because the feeder would merely act as an agitator in the bottom of the extractor.

To avoid such vortices, when the exhausted material is of very light specific gravity, I utilize a packer-screw of relatively small diameter as in Fig. 5 and this packer-screw being of smaller diameter than the feeder-screw must be run at a faster speed.

The speed at which the packer should be revolved is also determined by the nature of the material treated in the extractor because, if the chamber *f* is allowed to become about empty, the packer will act also as an agitator. From the above, it will be understood that the speed of the feeder-screw and the speed of the packer-screw have a certain relationship which can only be fixed for each material by actual experiments, and which will be different for the same kind of material when the moisture percentage varies. As a general rule, the ideal working condition will be when the unloading capacity of the feeder-screw and the unloading capacity of the packer-screw are such that the chamber *f* will be kept constantly filled with solid material. The solvent displaced under such conditions from the chamber *f* will minimize the possibility of the packer-screw acting as an agitator. It will be understood that in case the feeder-screw has a greater capacity than the packer-screw a jam in the chamber *f* will occur.

It will be understood that a decrease of the capacity of the packer-screw can occur through the sticking of sticky solid material either to the walls of the cylinder, including the ribs, or to the screw per se.

One of the main reasons for such decrease of capacity of the packer-screw is a certain back-slipping which occurs between the flights of the packer-screw, and that back-slipping is also different for different materials. By "back-slipping" I mean the tendency of the material to

work itself backwards, starting from the point adjacent to the end of the packer-screw, where the packing of the plug starts to take place. As will be seen, the theoretical displacement-capacity per revolution of the screw is decreased by this fact.

Another reason which contributes to a reduction in the capacity of the packer-screw is the pressure per square inch necessary to be applied by means of the valve 14 to the outer end of the plug in order to counterbalance the weight of the solvent in the extraction column.

While, therefore, I am unable to state the minimum capacity of the packer-screw in relation to the feeder-screw, it will be possible to state that the capacity of the packer-screw in relation to the feeder-screw should be such that, taking into consideration all the conditions of slipping, specific weight of the material, pressure of the valve, etc., the chamber *f* should always be full of solids.

For the preferred dimension of a twenty-five (25) ton per day extraction column, I suggest a 6 inch diameter, 7 inch pitch feeder-screw, and a 9 inch diameter, 4 inch pitch packer-screw; the revolution of the feeder-shaft being twelve (12) per minute and the revolution of the packer-shaft being fifteen (15) per minute, for material having specific gravity of soybeans, cotton seed, corn germ, etc., with moisture around eleven (11) percent.

In commercial installations, it will be a very simple matter to find the right relationship between these screws if both the packer-shaft and the feeder-shaft are individually driven and a variable speed reducer is inserted between the motor and the shaft of each screw.

In Figs. 6 and 7, I have shown a modified form of mechanism in which the shaft 110 of the feeder-screw 101 and the shaft 112' of the packer-screw 112 are on the same line but independently driven. Fig. 7 shows the preferred position of anchor brackets 113 for the joint bearing 113' for the two shafts 110 and 112'. The same general considerations will apply to this arrangement. Thus the opposite end of the shaft 110 is supported in a bearing 115 connected to the bottom of the extraction tank *I*' and is driven independently of the packer-screw shaft 112' through pinions 116 and 117 with shaft *S*² which in turn is connected to a suitable source of power such as a motor, not shown, while the opposite end of the shaft 112' is supported in a bearing 118 and rotated through pinions 119 and 120 from shaft *S*³ which is connected with any suitable source of power, such as an electric motor, not shown. In the construction shown in Figs. 6 and 7, the feeder-screw, as shown, has a single enlarged flight 101' at its outer end and feeds solid material into an intermediate packer feed chamber *f*^a corresponding to the chamber *f* of the box *F* from which chamber *f*^a the packer-screw 112^a will take such material and pack the same against the spring-pressed valve into a liquid-impervious plug, as hereinabove described.

In Fig. 8, I have shown, in an enlarged fragmentary vertical section, the end of the packing conduit and adjacent parts and particularly my preferred form of mounting and moving the cone-valve 14 on the outer end of the packer-shaft. Thus the bore of the cone-valve 14 preferably mounted has a bronze bushing 14^a slidable on the outer end of the shaft 12^b, which, beyond the tapered portion 12^b', is preferably straight or cylindrical in conformation. At the start of packing operation, the said cone-valve 14 will

be in closed position on its seat at the outer end of the packer-conduit as shown in the dotted lines in said Fig. 8. As the solid material moving through the packer-conduit is compressed, as hereinabove stated, it forces the valve outwardly to slide on the shaft to open position. When material is being continuously discharged between the valve and its seat, the compressed material continuously presses the valve back into the working position shown in the full lines in said Fig. 8. In said closed and opened positions, the valve 14 is held against rotation with the shaft 12^b by the friction of the spring or by other pressure-applying device. Usually the hollow cylindrical plug or stick of material, due to the pressure of the spring, disintegrates when the valve is pressed back to said position shown in full lines. The valve is, by the compressed plug, at times pushed beyond the fully-open position so shown in full lines, and I preferably provide means positioned adjacent to the fully-open position for causing the valve to be rotated by the shaft when such larger opening occurs. Such rotation of the valves is accomplished by fastening, on the shaft, a collar *C* rotatable with the shaft, mounting on the collar one or more clutch teeth *T* and providing the valve with gear teeth *T'*. The rotating action of the valve will thereupon assist in the disintegration of the hollow plug or stick. So soon as the disintegration occurs, the spring will thereupon force the valve forward in order to release engagement of the tooth *T* of the collar *C*.

Having described my invention, I claim:

1. A method of continuously forming liquid-impervious plugs in extraction units, which consists in continuously feeding, by a feeding conveyor of given capacity, exhausted solid material from an extraction unit into contact with a packing screw conveyor, moving said packing screw conveyor at a different velocity than the feeding conveyor and at a rate of speed that will provide, in said packing screw conveyor, greater capacity than the feeding conveyor, and continuously packing a plug of said exhausted material within said packing conveyor against a yieldable valve.

2. A method of continuously forming liquid-impervious plugs in extraction units, which consists in continuously feeding, by a feeding conveyor of given capacity, exhausted solid material from an extraction unit into a feed chamber on the same level as said feeding conveyor, then causing the movement of said material to a different level and into contact with a packing screw conveyor, moving said packing screw conveyor at a different velocity than the feeding conveyor and at a rate of speed that will provide, in said packing screw conveyor, greater capacity than the feeding conveyor, and continuously packing a plug of said exhausted material with said packing conveyor against a yieldable valve.

3. Apparatus for continuously forming liquid-impervious plugs for extraction units employed in the solvent extraction of oil-bearing solid materials, comprising, in combination, an extraction tank, a packer-conduit of uniform diameter connected with said extraction tank, a feeding conveyor in said tank for conveying exhausted solid material out of said tank and feeding the same into said packer-conduit, means for actuating said feeding conveyor, a packer-conveyor-screw of uniform diameter in said packer-conduit and a packer-valve at the end thereof, and means for

actuating said packer-conveyor-screw at a different velocity than the actuation of the feeder-conveyor.

4. Apparatus for continuously forming liquid-impervious plugs for extraction units employed in the solvent extraction of oil-bearing solid materials, comprising, in combination, an extraction tank, a packer-conduit of uniform diameter connected with said extraction tank, a feeding conveyor in said tank for conveying exhausted solid material out of said tank and feeding the same into said packer-conduit, means for actuating said feeding conveyor, a packer-conveyor-screw of uniform diameter in said packer-conduit and a packer-valve at the end thereof, said packer-conduit and packer-conveyor-screw being located on a different level than said feeder-conveyor, a feeder-box connected to said feeder conveyor and leading to said packer conduit, and means for actuating said packer-conveyor-screw at a different velocity than the actuation of the feeder-conveyor.
5. Apparatus for continuously forming liquid-impervious plugs for extraction units employed in the solvent extraction of oil-bearing solid materials, comprising, in combination, an extraction tank, a packer-conduit of uniform diameter connected with said extraction tank, a feeding conveyor in said tank for conveying exhausted solid material out of said tank and feeding the same into said packer-conduit, means for actuating said feeding conveyor, a packer-conveyor-screw of uniform diameter in said packer-conduit and a packer-valve at the end thereof, means for actuating said packer-conveyor-screw at a different velocity than the actuation of the feeder-conveyor, and hydraulic means for exerting a controlled pressure on said packer-valve.

6. Apparatus for continuously forming liquid-impervious plugs for extraction units employed in the solvent extraction of oil-bearing solid materials, comprising, in combination, an extraction tank, a packer-conduit of uniform diameter connected with said extraction tank, a feeding conveyor in said tank for conveying exhausted solid material out of said tank and feeding the same into said packer-conduit, means for actuating said feeding conveyor, a packer-conveyor-screw of uniform diameter in said packer-conduit and a packer-valve at the end thereof, means for actuating said packer-conveyor-screw at a different velocity than the actuation of the feeder-conveyor, and ribs disposed in the bore of said packer-conduit parallel to the axis thereof.

7. Apparatus for continuously forming liquid-impervious plugs for extraction units employed in the solvent extraction of oil-bearing solid materials, comprising in combination, an extraction tank, a packer-conduit of uniform diameter connected with said extraction tank, a feeding conveyor in said tank for conveying exhausted solid material out of said tank and feeding the same into said packer-conduit, means for actuating said feeding conveyor, a packer-conveyor-screw of uniform diameter in said packer-conduit and a packer-valve at the end thereof, means for actuating said packer-conveyor-screw at a different velocity than the actuation of the feeder-conveyor, resilient means for forcing said valve toward the end of said packer-conduit to form the plug and normally to disintegrate the same, and supplemental means for positively connecting said valve to the shaft to assist in disintegration of the plug being discharged from the packer-conduit.

MICHELE BONOTTO.
